FOLDING SWING STAGE

Peter P. Woboril, Sr., and Dwight D. Sturgeon,
Milwaukee, Wis., assignors to The Woboril
Company, Milwaukee, Wis., a corporation of
Wisconsin

Application May 25, 1951, Serial No. 228,146

3 Claims. (Cl. 304—15)

1

This invention relates to swing stages such as are used by painters and the like for working on the outside walls of buildings.

Among the objects of this invention are: To provide a swing stage that is light in weight, simple and efficient in operation and which can be readily and economically manufactured and used; to provide for collapsing the guard rail support structure into compact position with the main stage structure; to interconnect the stirrups to which the support cables are attached and the guard rail support structure so that they move conjointly; to permit relative translatory movement between the stirrups and the support structure; to pivotally mount the stirrups in the end rungs of the main stage structure; to employ tubular aluminum members in the fabrication of the stage and some of the component parts.

Other objects of this invention will, in part, be obvious and in part appear hereinafter.

This invention is disclosed in the embodiment thereof shown in the accompanying drawings and it comprises the features of construction, combination of elements and arrangement of parts which will be exemplified in the construction hereinafter set forth and the scope of the application of which will be indicated in the appended claims.

For a more complete understanding of the nature and scope of this invention, reference may be had to the following detailed description, taken together with the accompanying drawings, in which:

Figure 1 is a perspective view of a swing stage constructed in accordance with this invention, the stage being shown in the extended operative position;

Figure 2 is a view, similar to Figure 1, showing the swing stage in the folded or collapsed position;

Figure 3 is a detail sectional view taken generally along the line 3—3 of Figure 1;

Figure 4 is a detail sectional view, at an enlarged scale, taken generally along the line 4—4 of Figure 1;

Figure 5 is a detail sectional view, taken generally along the line 5—5 of Figure 4;

Figure 6 is a detail sectional view taken generally along the line 6—6 of Figure 1, certain parts of the back member being broken away for the purpose of conserving space; and

Figure 7 is a detail sectional view taken generally along the line 7—7 of Figure 6 to show the tubular construction of the back member.

Referring now particularly to Figures 1 and 2 of the drawings it will be observed that the reference character 10 designates, generally, a folding swing stage constructed in accordance with this invention. It includes a main stage struc-

2

ture, indicated generally at 11, which is constructed somewhat in the form of a ladder. The main stage structure 11 has associated therewith a guard rail and support structure therefor that are indicated, generally, at 12. They will be described in more detail hereinafter. The main stage structure 11 includes a generally rectangular frame that is designated, generally, at 13. The frame includes longitudinally extending front and back members 14 and 15 interconnected at their ends by end members 16. These members preferably are formed of a lightweight metal such as aluminum and are tubular as illustrated in Figure 7. Their ends are beveled as illustrated and they are welded together at the juxtaposed portions so as to provide a unitary construction. For illustrative purposes it is pointed out that the frame 13 is 192 inches long and twenty inches wide. However, it will be understood that it may be longer or shorter and wider or narrower as the occasion may require.

With a view to providing a support for painters or other workmen using the swing stage 10, intermediate rungs are located between the front 25 and back members 14 and 15. In the particular embodiment of the invention shown, nine intermediate rungs 19 are used. End rungs 20 are located near the end members 16 and are slightly larger in diameter than the intermediate rungs 19 for a purpose which will be apparent presently. Preferably the rungs 19 and 20 are formed of aluminum tubing and they project through suitable openings in the front and back members 14 and 15 and are secured thereto by welding.

Midway between the ends of the frame 13 there is positioned a truss arch 21 over which a guy wire 22 is trained. The ends of the guy wire 22 loop over the end rungs 20 and they can be tightened by means of turnbuckles 23 which are located in the guy wire 22 on opposite sides of the truss arch 21. For the purpose of spacing the swing stage from the wall of the building and at the same time reducing to a minimum friction herebetween when it is moved up and down rollers 45 24 are provided. They are carried by means of supports 25 which extend laterally from the front member 14 as shown in Figures 1 and 2 of the drawings.

It is desirable to space the rectangular frame 50 13 from the ground when the stage is there located. For this purpose leg members 26 can be employed. They are in the form of rectangular supports made of solid aluminum rod. As illustrated the rods forming the leg members 26 are bent to define three sides of a rectangle and the ends are arranged to be welded to the under sides of the end members 16.

Flooring 27 extends over the rungs 19 and 20. It may be formed of two sheets of aluminum, 60 one at each end of the frame 13, positioned there-

within and secured to the rungs 19 and 20 by welding or bolting as may be desired. It will be understood that wood planks can be employed in lieu of the aluminum sheets for the flooring 21.

With a view to supporting the swing stage 10 from depending cables in conventional manner, stirrups 29 are provided, one at each end of the frame 13 as shown. Each of the stirrups 29 is formed of solid aluminum rod and each has a centrally located eye section 30 to which the depending cables can be attached. As shown more clearly in Figure 4 of the drawings, each of the stirrups 29 has the ends 31 thereof turned inwardly and telescoped with a stirrup sleeve 32 which functions as a bushing and is rotatably mounted within the associated end rung 20 as shown. This provides a rigid construction and yet permits the pivoting of the stirrups 29 with respect to the frame 13.

Extending along and above the back member 15 is a guard rail 35. Preferably it is formed of tubular aluminum. The guard rail 35 is pivotally connected at 36 to rail supports 37 which are preferably formed of tubular aluminum. At their lower ends the rail supports 37 are pivotally connected at 38 to the back member 15. This pivoted construction permits the guard rail 35 to be swung from the extended position shown in Figure 1 to the collapsed position shown in Figure 2.

It is desirable that the stirrups 29 be interconnected with the guard rail 35. For this purpose stirrup brackets 39 are employed. They are formed preferably of aluminum rod and as shown, are looped over the ends of the guard rail 35. The ends of the stirrup brackets 39 are welded to the stirrups 29 so as to provide an integral construction.

In order to hold the stirrup brackets 39 in proper operative relation with respect to the guard rail 35 and at the same time permit relative translatory movement therebetween stirrup retainers 40 are located at the ends of the guard rail 35. As shown in Figures 1 and 2, they extend over the stirrup brackets 39 and there is considerable room for relative movement of the latter with respect to the guard rail 35.

Since certain changes can be made in the foregoing construction and different embodiments of the invention can be made without departing from the spirit and scope thereof, it is intended that all matter shown in the accompanying drawings and described hereinbefore shall be interpreted as illustrative and not in a limiting sense.

What is claimed as new is:

1. A folding swing stage comprising, in combination, a generally rectangular frame formed by elongated front and back members joined by end members, rungs extending between said front and back members in spaced relation, rollers and supports therefor carried by said front member and projecting therefrom to engage a building wall and space said frame therefrom, flooring extending over said rungs and disposed within said frame, a rail above and parallel to said back member, a plurality of rail supports pivoted at their lower ends to said back member and at their upper ends to said rail whereby the latter can be swung from an extended to a collapsed position with respect to said frame, stirrups pivoted in the ends of and extending above said frame for attachment to support cables, a stirrup bracket secured to each stirrup and looped over said rail near each end, and a stirrup retainer secured to the upper side of said rail and over-

lying each stirrup bracket for hingedly interconnecting them and permitting relative translatory movement therebetween when said rail and stirrups are swung between their extended and collapsed positions.

2. A folding swing stage comprising, in combination, a generally rectangular frame formed by elongated front and back members joined by end members, rungs extending between said front and back members in spaced relation, rollers and supports therefor carried by said front member and projecting therefrom to engage a building wall and space said frame therefrom, flooring extending over said rungs and disposed within said frame, a rail above and parallel to said back member, a plurality of rail supports pivoted at their lower ends to said back member and at their upper ends to said rail whereby the latter can be swung from an extended to a collapsed position with respect to said frame, stirrups pivoted in the end rungs and extending above said frame for attachment to support cables, a stirrup bracket secured to each stirrup and looped over said rail near each end, and a stirrup retainer secured to the upper side of said rail and overlying each stirrup bracket for hingedly interconnecting them and permitting relative translatory movement therebetween when said rail and stirrups are swung between their extended and collapsed positions.

3. A folding swing stage comprising, in combination, a generally rectangular frame formed by elongated front and back members joined by end members, leg members depending from said end members for spacing said frame from the ground, rungs extending between said front and back members in spaced relation, rollers and supports therefor carried by said front member and projecting therefrom to engage a building wall and space said frame therefrom, flooring extending over said rungs and disposed within said frame, a rail above and parallel to said back member, a plurality of rail supports pivoted at their lower ends to said back member and at their upper ends to said rail whereby the latter can be swung from an extended to a collapsed position with respect to said frame, stirrups pivoted in the end rungs and extending above said frame with integral centrally located eye sections for attachment to support cables, a stirrup bracket secured to each stirrup and looped over said rail near each end, and a stirrup retainer secured to the upper side of said rail and overlying each stirrup bracket for hingedly interconnecting them and permitting relative translatory movement therebetween when said rail and stirrups are swung between their extended and collapsed positions.
